THERMAL TESTING DEVICE

Carlisle K. Roos, Wheaton, Ill., assignor to
 United States Gypsum Company, Chicago, Ill.,
 a corporation of Illinois

Application November 10, 1932, Serial No. 641,993

6 Claims. (Cl. 35—12)

This invention relates to testing methods and devices, and has reference more particularly to thermal testing devices for demonstrating the transmission of heat through surfaces coated with 5 various materials.

It has been discovered that surfaces coated with bright metallic layers transmit much less heat than surfaces coated with dull or dull black coatings. It is desirable to provide a testing device 10 vice which will demonstrate this fact to persons in an effective and conclusive manner.

An object of this invention, therefore, is to provide a testing device for demonstrating the transmission of heat through sheets of material coated 15 with a variety of coatings.

Another object of this invention is to provide a thermal testing device in which sheets of material coated in various ways may be simultaneously tested from a common source of heat; 20 also to improve testing devices in other respects hereinafter specified and claimed.

Reference is to be had to the accompanying drawing forming a part of this specification, in which

25 Fig. 1 is a perspective view of my improved thermal testing box.

Fig. 2 is a perspective view showing the other side of the testing box with an electric lamp in position as a source of heat.

30 Fig. 3 is a sectional plan view through the testing device taken on line 3—3 of Fig. 1.

Fig. 4 is a plan view of the testing box unfolded in flat position, and

Fig. 5 is a view of the test box folded up for 35 insertion in a shipping envelope.

My thermal testing device is primarily intended as an advertising medium for demonstrating to the public the effectiveness of the metallic coating on a wallboard panel in improving the 40 heat insulating value of said panel. While the testing devices may take a variety of forms and shapes, they are preferably constructed in the form of the cubical box having a top wall 10, side walls 11, 12, 13, and 14, and a bottom wall 45 15. For convenience in manufacture and shipment, I prefer to make the test box of foldable cardboard of a shape when fully expanded, as shown in Fig. 4. Prior to shipment, an integral flap 16 on the side wall 13 is adhesively attached 50 to the edge of side wall 12. The carton is folded into compact form as seen in Fig. 5, for insertion in the shipping envelope. The bottom wall 15 and top walls 10 are provided each with an integral flap 18 for tucking within the box upon 55 assembling and before shipment. When the

carton is in the form as shown in Fig. 5, a small paper envelope 19 containing a paraffin or other candle 20, is adhesively attached to the flap 18. The side walls 11 and 13 are provided with integral flaps 21, which serve to reinforce the top 60 and bottom edges of the side walls, and extend inwardly into the interior of the box.

The inside surfaces of the side walls 11 and 13 are coated with dull black paint and metal foil, respectively, while the inside surface of the side 65 wall 12 is left blank. Numbers or other designating indicia 23 are printed on the outside surfaces of the side walls 11, 12, and 13, for the purpose of indicating the heat emissivity value of the respective side walls. An aperture 24 is provided 70 in the top wall 10 for the purpose of allowing the insertion of an electric lamp 25 through said aperture to extend into the inside of said box and supply a source of heat common to all of the side walls of the box. A comparatively large aperture 26 is provided in the side wall 14 so that the inside of the box can be observed by a person 75 during the testing procedure. In the outside center of each of the side walls 11, 12, and 13, there is printed one or more annular colored bands 28, 80 which serve to locate a central area 29 at the center of the side wall surface.

In operating the test device, the pasteboard 85 carton is removed from its shipping envelope and assembled, the candle envelope 19 preferably being removed from the flap 18 prior to assembling. A 60 or 100 watt electric lamp is next inserted in the box with the base of the bulb extending upwardly through the aperture 24, and screwed into a suitable electric light socket which may be suspended from a cord or electric fixture of any suitable type. The small candle 20 is removed from the envelope 19, lighted, a drop or spot of wax is deposited from the lighted candle on each of the three areas 29. The electric lamp is now 95 lighted and with a watch, the length of time necessary to melt the wax on each of the three sides 1, 2 and 3, is noted. It will be found that the spot on side wall No. 1, having the black surface, will melt first, the wax on side wall No. 2, having 100 a bare cardboard inner surface, will melt second, and the wax on side No. 3, coated on the inside with the metal foil, will remain firm and unfused long after the other two are melted. The box may be used over again several times for the same 105 test.

It will be understood that the type of test apparatus can be varied considerably, without departing from the spirit of the invention as defined in the appended claims. The box may be 110

- made of rigid material such as pressboard, and can be shipped to the users in assembled condition. Any source of heat may be used inside of the test box instead of the electric lamp, such as 5 a gas flame. The use of the fusible wax can be omitted and yet the vast difference in temperature between the outer surfaces of the respective side walls is readily apparent to the hand of the operator.
- 10 Having thus described my invention, I claim as new and desire to secure by Letters Patent:—
1. A thermal testing device comprising a plurality of sheets, each bearing an inside surface coating varying in character from sheet to sheet, 15 the surfaces of respective sheets opposite said coatings being adapted to receive a fusible material, said sheets being so arranged as to expose said coated surfaces to an inside common source of heat which fuses said fusible material at varying rates depending on the character of coatings.
  2. A thermal testing device comprising a cardboard box enclosing a source of heat and having a black surface coating and a metal foil surface coating on the inside surfaces of the side walls of 25 said box, and a fusible material on the outside surfaces of said coated side walls which will be fused at varying periods by transmission of heat through said coated side walls depending on the type of surface coating.
  3. A thermal testing device comprising defined areas of bright material and dark material contiguous to a common source of heat spaced equally 30 distant from and between said materials, and
